AUTOMATIC ICE MAKER

Theodore W. Rundell, Abington, Pa., assignor, by
mesne assignments, to Philco Corporation,
Philadelphia, Pa., a corporation of Pennsyl-
vania

Application December 28, 1943, Serial No. 515,958

8 Claims. (Cl. 62—2)

1

This invention relates to refrigeration, and has especial reference to a method and apparatus for the automatic production of ice masses.

More particularly, the invention is concerned with a method of and apparatus for the automatic and sequential freezing of ice masses for domestic consumption, and the storing of the same in readily available form.

In domestic refrigerators now in general use, it is common to provide a freezing chamber within which separate ice trays are inserted, each filled with water to be frozen into masses commonly called cubes. After the cubes have been formed, it is necessary to remove the tray from the refrigerator, and to free the cubes from the tray by the use of warm water, or some like expedient. Following this, the tray must be refilled and returned to the refrigerator for a re-initiation of the freezing cycle.

Such a process is not only time-consuming and inconvenient, but in addition, is disadvantageous as all of the ice cubes must be freed from a container, even though the user may require only a small number thereof. Moreover, ice obtained in this way cannot readily be stored for future use, since the film of water present upon the freed cubes causes them to freeze together upon replacement within the freezing chamber. Still further, the ice tray is generally tightly bonded to the supporting surface of the freezing compartment and, as a consequence, requires the use of levers or other special devices to effect removal thereof. These and other difficulties have recently given rise to a very considerable commercial demand for refrigerators capable of automatic and continuous formation of ice, and of maintaining the ice in such a condition that it may be removed piece by piece, as and when required.

It is, therefore, a primary object of the present invention to overcome the aforesaid difficulties by the provision of a method of and apparatus for the automatic freezing, freeing, and storing of a readily accessible supply of ice.

More particularly, it is an object of the invention to provide an apparatus in which ice forming molds are automatically supplied with water to be frozen, and in which thermo-sensitive means is provided for freeing the frozen masses from the mold member, after the completion of the freezing cycle.

Still more particularly, the present invention has as an object, the provision of ice making apparatus having a bi-metallic member for freeing the frozen masses from the mold, and for

2

effecting automatic control of the water supply to said mold.

It is also an object of the invention to store separate ice masses in such a manner that they are neither bonded to the molding member, nor frozen to one another.

A further object of the invention resides in the provision of an ice cube forming and dispensing device, which obviates the disadvantages of the ice trays described above, by automatically freezing water into ice masses and subsequently dispensing said masses, one by one, without wastage of the remaining masses and without requiring removal of the latter from the freezing compartment.

The invention also contemplates the provision of an ice making apparatus in which ice production is automatically discontinued when the storage capacity of the unit has been reached.

A further object relates to a novel method of and apparatus for producing freely accessible ice cubes, for storage as set forth, said method and apparatus functioning in continuous cycle until the storage container is fully loaded.

25 A more specific object of the invention is to provide means for breaking the bond between the ice masses and the mold members, by use of a bimetallic thermo-sensitive disk arranged as one wall portion of the mold member.

30 The invention further contemplates the provision of apparatus of the general type set forth, which is exceedingly compact and enables location of the operating components and supply system exteriorly of the freezing chamber.

35 It is also an object to provide an apparatus of the type set forth, which embodies novel means for preventing premature freezing of the water to be delivered to the ice molding members.

These and other objects and advantages will 40 be best understood by a consideration of the following description in conjunction with the accompanying drawings, in which:

Fig. 1 is a perspective view of a refrigerator embodying the invention, portions being broken away for the sake of clarity in illustration;

Fig. 2 is an enlarged sectional view of a portion of the apparatus illustrated in Fig. 1;

Fig. 3 is a sectional view taken on line 3—3 of Fig. 2;

45 Fig. 4 is an enlarged sectional view of the ice molding member and certain associated apparatus;

Fig. 5 is a fragmentary perspective view, illustrating certain details of the mold member;

Fig. 6 is a view in perspective of the bi-metallic

thermo-sensitive element employed in the mold member;

Fig. 7 is a perspective view of one of the ice masses produced in accordance with the present invention, and

Fig. 8 is a perspective view illustrating one feature of the invention.

With particular reference to Fig. 1 of the drawings, the reference character 2 designates, generally, a domestic refrigerator of the mechanical type including an outer shell 3, which may be of any well known type and construction, and an inner metal shell or liner member 4 which forms the walls of the food storage space indicated at 5, said space preferably being fitted with suitable shelves (not shown). Vertical and horizontal breaker strips 6 and 7, respectively, of low thermal conductivity, are fitted around the forward marginal edge of the cabinet opening; while thermal insulation, indicated at 8, completely surrounds the inner liner member. It will be understood that the cabinet is provided with a door adapted to seat in the plane of the breaker strips 6 and 7, said door having been omitted from the drawing for the sake of clarity in illustration. As revealed by the broken-away portions of the cabinet shells, there is a machinery compartment 9 located beneath the food storage space, which compartment houses the compressor unit indicated at 10. A horizontal floor member 11 divides the machinery compartment from the upper portions of the cabinet, the insulation 8 being continued thereacross. As the particular refrigerant flow circuit employed to effect cooling of the food storage space forms no part of the present invention, such flow passages and the connections thereto have not been illustrated in the drawings.

In the embodiment illustrated, a double thickness partition 12 provides a floor for the food storage compartment (this partition preferably being of the type known commercially by the trade name "Thermopane"), and a gasket 13, best seen in Fig. 2, is interposed between the partition members and the adjacent wall portions of the inner liner 4. Mounted beneath this partition is a low-temperature evaporator designated generally by the reference character 14, which comprises a horizontal floor 15, vertical side walls 16 and a central vertical wall 17, dividing the space within said evaporator into a pair of compartments maintained at freezing temperatures. As shown in Fig. 2, the evaporator is provided with an outwardly turned flange portion 18 at the free edge of each of the vertical walls 16, by means of which the evaporator is supported in the cabinet by connections effected at 19 in the general plane of the partition member 12.

In accordance with the invention, and as first briefly described in connection with Figs. 1, 2 and 3, the novel apparatus of the present invention comprises a plurality of ice molding members or cups 20 formed in the lower wall of the evaporator 14, to which cups water is fed from a storage tank 21 located within the food storage compartment 5, the level of the water in the cups being determined and maintained by some suitable float valve mechanism indicated generally by the cylindrical housing 22. The operating cycle, as will be fully described hereinafter, includes filling of the cups 20 to the desired level, freezing of the contents thereof, and subsequent extrusion or forcing out of the ice masses from the cups by means of a temperature responsive element. This upward movement automatically conditions the mechanism to permit the inflow of additional water to fill the space left

by the raising of the ice block, after which the freezing cycle is re-initiated. Walls 23 and 23a extend upwardly from the floor of the evaporator, said walls running from the forward to the rearward edge of the evaporator in general parallelism with the side walls 16 and closely adjacent to the cups 20. A pair of cover members 24-24 are slidingly supported in the evaporator side wall and the partitions 23 and 23a define an enclosed space around the cups 20. To obtain access to the frozen ice masses, the cover members may be drawn forwardly (see Fig. 8), suitable handles 24a being provided for the purpose.

Describing the ice forming and storing apparatus with more particularity, and with special reference to Figs. 2 to 6 inclusive, it will appear that water is delivered from the storage tank 21 (maintained at a temperature above freezing) to a downwardly extending pipe 25, and into the aforesaid float chamber 22. While a reservoir has been illustrated and described which is adapted to be placed within the food storage area, it will be clear that the inlet line 25 of the water supply feed apparatus could be directly connected with the house water supply, if such is desired. From the float chamber, as best seen in Fig. 3, a passage 26 delivers the water to a supply header 27, which is arranged centrally beneath the cuffed portion of the evaporator 14 to supply water to all the cups, by means of upwardly extending short connections 28. Each of these connection passages 28 passes upwardly through a vertically arranged hollow conduit 29, the lower end of which passes through the floor 11 and is in open communication with the motor-compressor compartment.

The purpose of these conduits is to conduct sufficient heat from the compressor upwardly to the region of the tubing 28, to insure that freezing will not occur in said tubes, that is, below the level of the lower wall of the cups 20. In addition, and to further insure delivery of warm water to the cups 20 (for a purpose which will appear later) the supply header 27 is located closely adjacent to the top wall 11 of the machine compartment.

Making reference to Fig. 4, the members 20 are each surrounded by a space 30, which is a part of the refrigerant evaporator circuit and provides for rapid freezing of the water delivered to the cups. In order to maintain a more constant temperature in the vicinity of the cups 20, the refrigerant flow passages 30 are preferably arranged so as to constitute a portion of the refrigerant inlet supply header. Although the refrigerant will be, at least to some extent, active in this zone, this arrangement will maintain the passages 30 in a substantially flooded condition, thereby serving to maintain a more constant temperature throughout the operating cycle.

Although any convenient form of evaporator circuit may be employed, there has been illustrated an evaporator of the type having a balanced central feed to the bottom wall thereof (through passage 31 appearing in Fig. 2) after which the refrigerant passes upwardly through parallel connections 32 to the exhaust headers 33, one of which is illustrated in Fig. 3.

Still with reference to Fig. 4, it will be seen that the cups 20 are of generally frusto-conical configuration and are provided with a lower cylindrical part 34. Within this cylindrical portion there is securely mounted an internally threaded flange portion 36 adjacent its lower edge. As shown at 37 in the drawing, the upper surface of the flange portion is secured to adja-

cent portions 38 of the evaporator, as by means of welding. A centrally bored plug member 39 has threaded engagement with the inside surface of the sleeve 35 and the water supply pipe 28 is mounted within said plug and is secured as by means of the weld indicated at 40. Plug 39 has a lower annular extension 41 of reduced size, to which is secured the upper end of conduit 29. A gasket is shown at 42, being interposed between plug 39 and the flanged portion of sleeve 35; and a threaded collar 43 serves to maintain the desired gasket pressure.

As illustrated in Figs. 4 to 6, inclusive, a bi-metal thermo-sensitive disk 44 is positioned in the lower portion of each of the cups 20, plug member 39 being shaped to provide a seat for the disk when said disk is in the position shown in full lines. This disk is movable with a snap-action between the upper and lower positions shown in Fig. 4 in dotted and full lines, respectively. The upper portion of sleeve 35 is formed so as to overlie the adjacent edges of the bi-metal disk, as shown at 45, in order to maintain the disk in the proper position and to provide a reaction point for its over-center toggle action. The bi-metal element carries a valve member 46 fixed to the lower surface thereof, which is adapted to cooperate with a valve seat 47 to control the passage of water through the delivery system. It will be understood that this valve is carried upwardly when the disk moves to the position shown in dotted lines.

As best seen in Fig. 5, each of the disks has a number of apertures 48, through which water is delivered to the cup as will be described. Plug member 39 is fitted with upstanding projections 49 for registry with the apertures 48 when the disk moves to its lower position. These projections serve to close the openings 48 when the disk is in its lower position, in order to prevent formation of ice in the disk apertures. As may be seen from a comparison of Figs. 5 and 6, the cup 20 has a projection 50 which is adapted to cooperate with a slot 51 formed in the edge of the bi-metal disk. Cooperation between the elements 50 and 51 prevents rotation of the disk within its seat 45, which rotative movement would destroy the desired registry between the water flow apertures 48 and the projections 49.

In assembling the cup structure, the bi-metal disk is first snapped into position beneath the overhanging portions 45 of the sleeve 35, and the plug 39 threaded into said sleeve, after which the resultant assembly is fitted within the flange portion 34 of the cup. Application of the pipes 28 and 29 and the collar 43 completes the assembly.

It should be noted that a ring 52, of rubber or the like, surrounds the top of each of the cups 20 and is provided with an annular lip 53 extending somewhat into the cup opening, said lip having a number of slots formed thereabout. This ring is maintained in position by an apertured plate 54, provided with downwardly turned portions 55 adapted to engage the ring. As shown in Fig. 2, the plate 54 is secured to the fixed evaporator structure.

The operation of the device is as follows:

Let it be considered first that the evaporator 14 is operating, and that no water has as yet been delivered to the cups 20; in such circumstance the evaporator circuit, including the enlarged flow passages 30, will lower the temperature of the cups 20 and therefore the disks 44 to some predetermined minimum temperature, for

example in the neighborhood of from 0° to 15° F. The existence of this predetermined minimum temperature operates to raise the thermo-sensitive disk to its upper position (shown in dotted lines) thereby opening the valve 46 and the ports 48. Water now flows from the supply tank 21 and is delivered to the cups through pipes 25 and 28, as described, under regulation by the float valve device 22 and as indicated at 56 in Fig. 4.

The water thus introduced to the cups 20 will be warm as compared to the temperature of said cup and of the disk 44, by virtue of the heat exchange taking place through the conduit 29, and also due to the fact that the water supply header 27 is located immediately above the machine compartment. When the cup has been completely filled with relatively warm water, to the level indicated at 56 in Fig. 4, the temperature of the bi-metal disk 44 will be raised sufficiently to cause it to snap back to its lower position shown in full lines, thereby closing the valve 46 against its seat 47, and plugging the disk flow ports 48 to prevent formation of ice therein. It will be understood that bi-metal disks are not new in the art, per se, but that the characteristics of the disk must be predetermined so as to cause it to snap between its upper and lower positions in response to the differential temperatures existing during the operating cycle. The disk is further of a type which is capable of exerting an upward force sufficient to break the bond existing between the ice block and the mold member, and to raise said block upwardly a distance equal to the complete travel of said disk.

Due to the action of the evaporator portions 30, the liquid contained in the cup 20 is then frozen, during which time the disk remains in its lower position until completion of the freezing operation. This maintenance of the lower disk position is readily accomplished, by virtue of the fact that at the freezing point heat abstracted by the evaporator is primarily effecting a change of state in the water, rather than serving to substantially lower the temperature of cup 20 and of disk 44.

After the freezing operation is completed, the temperature of the cup and of the block of ice therein will be drawn down until a predetermined minimum is reached (for example from 0° to 15° F.), at which time the disk snaps to its upward position, freeing the bond between the ice and the mold and extruding or forcing the ice block upwardly until it projects out of the cup. The reference numeral 57 appearing in Fig. 4, indicates a dot and dash representation of the position of the ice block after it has been raised. As the ice block is raised, the resilient lip portion 53 is forced backwardly out of the cup opening under the influence of the rising block and thereafter returns to the position illustrated, in which it will maintain the mass of ice in its raised position, without the support of disk member 44.

At this period in the operating cycle, water will again flow into the cup 20 in the manner described above, completely filling the space between the raised block of ice and the side walls of the cup, to the level determined by the float valve device. The slots 53a are provided in the lip edge, in order to insure proper operation of the level-determining device, by maintaining the area immediately above the water in the cups at atmospheric pressure throughout the operating cycle. From this point on the cycle is repeated, with the thermo-sensitive disk snapping to its lower position and the freezing of the water being reinitiated. The cyclic operation of the mecha-

nism will continue until a cylinder of ice is formed in each cup, which projects upwardly a distance sufficient to make contact with the horizontally extending shelf 24, shown in Fig. 2. An ice block formed in this way is illustrated at 58 in Fig. 7, said figure indicating the general shape of the complete ice masses produced by the apparatus of this invention.

When the cylinder of ice has reached the lower surface of cover member 24, it is no longer possible for the valve 46 to be opened by the bi-metal disk and the freezing cycle is automatically terminated. However, when the shelf restraint is removed (in which connection see Fig. 8) by sliding said shelf forwardly out of contact with the upper portions of the cylinders of ice, the above described cycle will recommence, thereby freeing the ice block from the cup and permitting the ready removal thereof. It will be understood, of course, that the cover member 24 is drawn forwardly only a sufficient distance to expose and free the number of ice cubes desired, the balance of said cubes remaining in contact with the under surface of the cover. When the ice has been removed from any cup and the shelf is repositioned, an accumulation of ice is again built up in said cup to the level of the shelf.

From the foregoing description, it will be seen that the invention provides a completely automatic apparatus for the sequential production of ice, said apparatus further serving to store the ice in readily available form and accessible position. The proportions of the ice blocks may be varied, as desired, but said blocks are preferably of such a size that one thereof is adequate for use with the ordinary tumbler. Further, it will be seen that the invention is capable of automatic production and dispensing of ice, without wastage of any of the ice produced, and without necessitating the removal of any ice from the freezing compartment except as and when needed.

In the method aspect, the invention includes the novel concept involved in cyclically effecting: automatic and controlled water supply, followed by formation of ice and movement thereof to a free and accessible position, concurrently effecting additional inflow of water to be frozen and termination of the process when the storage capacity has been reached, by virtue of a restraining force created by the dimensional increase of the ice block itself.

While a preferred structural embodiment of the invention has been illustrated, it should be understood that the details thereof are merely illustrative, and that the invention contemplates such changes and modifications as may come within the scope of the annexed claims. The terms "extrusion" and "extruding" herein are used in the broad sense of those terms to mean to thrust, force, press or push out.

I claim:

1. A method for the cyclic production of ice, which comprises supplying water to an ice-molding receptacle, freezing said water to form an ice mass, freeing the mass from the mold member automatically in response to the temperature of the mass and effecting positive movement of said mass to a position in which at least a portion thereof is displaced from the freezing zone of said receptacle, supplying additional water to the molding receptacle, freezing said additional water in contact with the mass previously frozen to effect a bond therewith, effecting controlled cyclic repetition of the aforesaid steps until a mass of a desired size has been formed, and then effecting

automatic termination of the process by virtue of a restraining force created by the dimensional increase of said ice mass.

5 2. A method for the cyclic production of ice, which comprises supplying water to an ice-molding receptacle, freezing said water to form an ice mass, freeing the mass from the mold member automatically in response to the temperature of the mass and effecting positive movement of the mass toward a barrier and partially out of the mold member, effecting additional inflow of water to be frozen, freezing said additional water while in contact with the previously frozen mass to effect a bond therewith, effecting controlled cyclic 10 repetition of the aforesaid steps until said mass makes contact with the barrier, and utilizing the restraining force so created to effect automatic termination of the process.

15 3. Apparatus for forming and dispensing ice masses, said apparatus comprising a mold member adapted to receive water to be frozen into ice; means for sequentially and cyclically supplying water to said mold member freezing said water, and at least partially extruding the ice 20 thus formed from the mold member, said means including a thermo-sensitive element operative upon the completion of each freezing cycle to effect said extrusion of the ice and to reinitiate the water supply.

25 4. In apparatus for forming and dispensing ice masses, a mold member adapted to receive water to be frozen, means for freezing the water to form an ice mass, a bimetallic thermo-sensitive element adapted to free said mass from the mold member and to effect movement thereof to an accessible position at the completion of the freezing cycle, and means for maintaining the mass 30 in such position.

35 5. In ice forming apparatus, a refrigerated mold; means for supplying water to the mold for conversion into ice; temperature responsive means at the bottom of the mold movable under differing temperature conditions between an extended position, wherein said means projects into the ice freezing area of the mold cavity, and a retracted position withdrawn from said area; and a valve controlling the said water supply and operatively associated with the temperature responsive means so as to provide for admission of water to the mold when the said means is extended and for exclusion of the water when the said means is retracted.

40 6. In ice forming apparatus, a refrigerated mold, means for supplying water to the mold for conversion into ice, a valve controlling said supply, and a temperature responsive device constituting a means for automatically displacing the ice in the mold after the entire water content of the mold has been frozen and for simultaneously actuating the valve to admit additional water to the mold, said device being operative under the influence of the relatively elevated temperature of the admitted water to return the valve to water excluding position.

45 7. In apparatus for the formation of ice by continuous cyclic operation, a refrigerated mold, means for supplying water to the mold for conversion into ice, a valve controlling said supply, a thermo-sensitive device in thermal association with the mold constituting a means for automatically displacing the ice in said mold to afford space for additional water and for simultaneously actuating the valve to admit said water, said device being actuated to effect said displacement by relatively low temperatures occurring in

the mold after the entire water content thereof is frozen, and said device being actuated by the relatively high temperature of the simultaneously admitted water to return the valve to water-excluding position.

8. In ice forming apparatus, a refrigerated mold, means for supplying water to the mold for conversion into ice, a valve controlling said supply, thermo-sensitive means in thermal association with the mold and movable to an extended position under the influence of relatively low temperatures occurring when the entire water content of the mold is frozen, said means in the extended position projecting into the water-freezing area of the mold cavity so as to displace the body of ice in the mold, said thermo-sensitive means being associated with the valve and operative when moving to said extended position to effect opening of the valve for admission of additional water to the mold, and said thermo-sensitive means being movable to a retracted position withdrawn from said area of the mold cav-

ity under the influence of relatively elevated temperatures occurring as a result of said water admission and being operative in said retractive movement to effect return of the valve to a closed position excluding water from the mold.

THEODORE W. RUNDELL.
